ABSTRACT

A display device includes: a timing controlling circuit configured to generate an image data, a data control signal and a gate control signal; a data driving circuit configured to generate a data signal, a stress signal and an anode reset signal using the image data and the data control signal; a gate driving circuit configured to generate a gate1 signal, a gate2 signal, an emission1 signal and an emission2 signal using the gate control signal; and a display panel configured to display an image using the data signal, the gate1 signal, the gate2 signal, the emission1 signal and the emission2 signal, wherein a width of a stress period between a rising timing of the gate2 signal and a rising timing of the emission1 signal is changed according to a luminance band of the image.

The present application claims the priority benefit of Republic of Korea Patent Application No. 10-2023-0011819, filed in Republic of Korea on Jan. 30, 2023, which is hereby incorporated by reference in its entirety.

BACKGROUND

Technical Field

The present disclosure relates to a display device, and more particularly, to a display device where deterioration such as a flicker is reduced or minimized by changing a stress period according to a luminance band in a holding subframe of a relatively low frequency and a method of driving the display device.

Discussion of the Related Art

Recently, with the advent of an information-oriented society, the interest in information displays for processing and displaying a massive amount of information and the demand for portable information media have increased. As such, a display field has rapidly advanced. Thus, various light and thin flat panel display devices have been developed and highlighted.

Among the various flat panel display devices, an organic light emitting diode (OLED) display device is an emissive type device that does not include a backlight unit used in a non-emissive type device such as a liquid crystal display (LCD) device. As a result, the OLED display device has advantages in a viewing angle, a contrast ratio and a power consumption to be applied to various fields.

The OLED display device displays an image by changing a frequency (refresh rate) according to a mode. For example, the OLED display device may display an image with about 60 Hz in a real use mode and with about 1 Hz in a standby mode.

When the OLED display device is driven with a relatively low frequency such as about 1 Hz, a gate signal and a data signal are generated and inputted during a refresh subframe of a single frame (1F), and generation and input of a gate signal and a data signal are stopped during a holding subframe of a single frame (1F). However, since deterioration such as a flicker occurs due to a luminance deviation between the refresh subframe and the holding subframe, a display quality of an image displayed by the OLED display device is degraded.

SUMMARY

Accordingly, the present disclosure is directed to a display device that substantially obviates one or more of the problems due to limitations and disadvantages of the related art.

An object of the present disclosure is to provide a display device where deterioration such as a flicker is reduced or minimized and a display quality is improved by changing a width of a stress period where a stress signal is applied according to a luminance band during a holding subframe of a relatively low frequency and a method of driving a display device.

Another object of the present disclosure is to provide a display device where a hysteresis is improved and a flicker index is reduced or minimized due to reduction of a refresh-holding gap by changing a width of a stress period according to a high level signal and a stress signal during a holding subframe of a relatively low frequency and a method of driving a display device.

Additional features and advantages of the disclosure will be set forth in the description which follows, and in part will be apparent from the description, or can be learned by practice of the disclosure. These and other advantages of the disclosure will be realized and attained by the structure particularly pointed out in the written description and claims hereof as well as the appended drawings.

To achieve these and other advantages and in accordance with the purpose of the present disclosure, as embodied and broadly described herein, a display device includes: a timing controlling circuit configured to generate an image data, a data control signal and a gate control signal; a data driving circuit configured to generate a data signal, a stress signal and an anode reset signal using the image data and the data control signal; a gate driving circuit configured to generate a gate1 signal, a gate2 signal, an emission1 signal and an emission2 signal using the gate control signal; and a display panel configured to display an image using the data signal, the gate1 signal, the gate2 signal, the emission1 signal and the emission2 signal, wherein a width of a stress period between a rising timing of the gate2 signal and a rising timing of the emission1 signal is changed according to a luminance band of the image.

In another aspect, a method of driving a display device includes; generating an image data, a data control signal and a gate control signal; generating a data signal, a stress signal and an anode reset signal using the image data and the data control signal; generating a gate1 signal, a gate2 signal, an emission1 signal and an emission2 signal using the gate control signal; and displaying an image using the data signal, the gate1 signal, the gate2 signal, the emission1 signal and the emission2 signal, wherein a width of a stress period between a rising timing of the gate2 signal and a rising timing of the emission1 signal is determined according to a luminance band of the image.

It is to be understood that both the foregoing general description and the following detailed description are explanatory and are intended to provide further explanation of the disclosure as claimed.

BRIEF DESCRIPTION OF THE DRAWINGS

The accompanying drawings, which are included to provide a further understanding of the disclosure and are incorporated in and constitute a part of this specification, illustrate embodiments of the disclosure and together with the description serve to explain the principles of the disclosure. In the drawings:

FIG. 1 is a view showing a display device according to a first embodiment of the present disclosure;

FIG. 2 is a cross-sectional view showing a display panel of a display device according to a first embodiment of the present disclosure;

FIG. 3 is a block diagram showing first and second gate driving units and a display panel of a display device according to a first embodiment of the present disclosure;

FIG. 4 is a block diagram showing first and second gate driving units and a display panel of a display device according to a second embodiment of the present disclosure;

FIG. 5 is a circuit diagram showing a subpixel of a display device according to a first embodiment of the present disclosure;

FIG. 6 is a view showing a plurality of signals in a refresh subframe of a display device according to a first embodiment of the present disclosure;

FIG. 7 is a view showing a plurality of signals in a holding subframe of a display device according to a first embodiment of the present disclosure;

FIG. 8 is a flow chart showing a method of driving a display device according to a first embodiment of the present disclosure;

FIG. 9 is a table showing a flicker index of a display device according to a first embodiment of the present disclosure; and

FIG. 10 is a view showing a luminance change of a display device according to a first embodiment of the present disclosure.

DETAILED DESCRIPTION

Advantages and features of the present disclosure, and implementation methods thereof will be clarified through following example embodiments described with reference to the accompanying drawings. The present disclosure may, however, be embodied in different forms and should not be construed as limited to the example embodiments set forth herein. Rather, these example embodiments are provided so that this disclosure can be sufficiently thorough and complete to assist those skilled in the art to fully understand the scope of the present disclosure. Further, the present disclosure is only defined by scopes of claims.

The shapes, sizes, ratios, angles, numbers, and the like, which are illustrated in the drawings to describe various example embodiments of the present disclosure, are merely given by way of example. Therefore, the present disclosure is not limited to the illustrations in the drawings. Like reference numerals refer to like elements throughout the specification, unless otherwise specified.

In the following description, where the detailed description of the relevant known function or configuration may unnecessarily obscure a feature or aspect of the present disclosure, a detailed description of such known function or configuration may be omitted or a brief description may be provided.

Where the terms "comprise," "have," "include," and the like are used, one or more other elements may be added unless the term, such as "only," is used. An element described in the singular form is intended to include a plurality of elements, and vice versa, unless the context clearly indicates otherwise.

In construing an element, the element is to be construed as including an error or a tolerance range even where no explicit description of such an error or tolerance range is provided.

Where positional relationships are described, for example, where the positional relationship between two parts is described using "on," "over," "under," "above," "below," "beside," "next," or the like, one or more other parts may be located between the two parts unless a more limiting term, such as "immediate(ly)," "direct(ly)," or "close(ly)" is used. For example, where an element or layer is disposed "on" another element or layer, a third layer or element may be interposed therebetween.

Although the terms "first," "second," A, B, (a), (b), and the like may be used herein to refer to various elements, these elements should not be interpreted to be limited by

these terms as they are not used to define a particular order or precedence. These terms are only used to distinguish one element from another. For example, a first element could be termed a second element, and, similarly, a second element could be termed a first element, without departing from the scope of the present disclosure.

The term "at least one" should be understood to include all combinations of one or more of related elements. For example, the term of "at least one of first, second and third elements" may include all combinations of two or more of the first, second and third elements as well as the first, second or third element.

The term "display device" may include a display device in a narrow sense such as liquid crystal module (LCM), an organic light emitting diode (OLED) module and a quantum dot (QD) module including a display panel and a driving unit for driving the display panel. In addition, the term "display device" may include a complete product (or a final product)

10 including the LCM, the OLED module and the QD module such as a notebook computer, a television, a computer monitor, an equipment display device including an automotive display apparatus or a shape other than a vehicle, and a set electronic apparatus or a set device (or a set apparatus) 15 including the LCM, the OLED module and the QD module such as a mobile electronic apparatus of a smart phone or an electronic pad.

Accordingly, a display device of the present disclosure may include an applied product or a set device of a final user's device including the LCM, the OLED module and the QD module as well as a display device in a narrow sense such as the LCM, the OLED module and the QD module.

According to circumstances, the LCM, the OLED module and the QD module having a display panel and a driving unit may be expressed as "a display device", and an electronic apparatus of a complete product including the LCM, the OLED module and the QD module may be expressed as "a set device." For example, a display device in a narrow sense may include a display panel of a liquid crystal, an organic light emitting diode and a quantum dot and a source printed circuit board (PCB) of a control unit for driving the display panel, and a set device may further include a set PCB of a set control unit electrically connected to the source PCB for controlling the entire set device.

40 45 The display panel of the present disclosure may include all kinds of display panels such as a liquid crystal display panel, an organic light emitting diode display panel, a quantum dot display panel and an electroluminescent display panel. The display panel of the present disclosure is not limited to a specific display panel of a bezel bending having a flexible substrate for an organic light emitting diode display panel and a lower back plate supporter. A shape or a size of the display panel for the display device of the present disclosure is not limited thereto.

50 55 60 For example, when the display panel is an organic light emitting diode display panel, the display panel may include a plurality of gate lines, a plurality of data lines and a subpixel in a crossing region of the plurality of gate lines and the plurality of data lines. The display panel may include an array having a thin film transistor of an element for selectively applying a voltage to each subpixel, an emitting element layer on the array and an encapsulating substrate or an encapsulation part covering the emitting element layer. The encapsulation part may protect the thin film transistor and the emitting element layer from an external impact and may prevent or at least reduce penetration of a moisture or an oxygen into the emitting element layer. In addition, a

layer on the array may include an inorganic light emitting layer, for example, a nano-sized material layer or a quantum dot.

The thin film transistor of the present disclosure may include one of an oxide thin film transistor, an amorphous silicon thin film transistor, a low temperature polycrystalline silicon thin film transistor.

Features of various embodiments of the present disclosure may be partially or entirely coupled to or combined with each other. They may be linked and operated technically in various ways as those skilled in the art can sufficiently understand. The embodiments may be carried out independently of or in association with each other in various combinations.

Hereinafter, a display device according to various example embodiments of the present disclosure where an influence on an oxide semiconductor layer of a thin film transistor of a driving element part is reduced by shielding a light emitted and transmitted from a subpixel and/or a light inputted from an exterior will be described in detail with reference to the accompanying drawings.

FIG. 1 is a view showing a display device according to a first embodiment of the present disclosure. The display device may be an organic light emitting diode (OLED) display device.

In FIG. 1, a display device 110 according to a first embodiment of the present disclosure includes a timing controlling unit 120, a data driving unit 125, first and second gate driving units 130 and 135 and a display panel 140.

The timing controlling unit 120 (e.g., a timing controlling circuit) generates an image data, a data control signal and a gate control signal using an image signal and a plurality of timing signals including a data enable signal, a horizontal synchronization signal, a vertical synchronization signal and a clock signal transmitted from an external system such as a graphic card or a television system. The image data and the data control signal are transmitted to the data driving unit 125, and the gate control signal is transmitted to the first and second gate driving units 130 and 135.

The data driving unit 125 (e.g., a data driving circuit) generates a data signal (a data voltage) Vdata (of FIG. 5) as well as a stress signal Vobs and an anode reset signal Var described later using the data control signal and the image data transmitted from the timing controlling unit 120 and transmits the data signal Vdata to a data line DL of the display panel 140.

The first and second gate driving units 130 and 135 (e.g., a first gate driving circuit and a second gate driving circuit) generate a gate signal (a gate voltage) Sc1 and Sc2 (of FIG. 5) and an emission signal (an emission voltage) Em1 and Em2 (of FIG. 5) using the gate control signal transmitted from the timing controlling unit 120 and applies the gate signal Sc1 and Sc2 and the emission signal Em1 and Em2 to a gate line GL of the display panel 140.

The first and second gate driving units 130 and 135 may have a gate in panel (GIP) type to be formed in a non-display area NDA of a substrate of the display panel 140 having the gate line GL, the data line DL and a pixel P in the display area DA.

Although the first and second gate driving units 130 and 135 are disposed in both side portions of the display panel 140 in the embodiment of FIG. 1, one gate driving unit may be disposed in one side portion of the display panel 140 in another embodiment.

The display panel 140 includes a display area DA at a central portion thereof and a non-display area NDA surrounding the display area DA. The display panel 140 dis-

plays an image using the gate signal Sc1 and Sc2, the emission signal Em and the data signal Vdata. For displaying an image, the display panel 140 includes a plurality of pixels P, a plurality of gate lines GL and a plurality of data lines DL in the display area DA.

Each of the plurality of pixels P includes a plurality of subpixels including first to fourth subpixels SP1 to SP4, and the gate line GL and the data line DL cross each other to define the first to fourth subpixels SP1 to SP4. Each of the first to fourth subpixels SP1 to SP4 is connected to the gate line GL and the data line DL. For example, the first to fourth subpixels SP1 to SP4 may correspond to red, green, blue and white colors, respectively.

When the display device 110 is an OLED display device, each of the first to fourth subpixels SP1 to SP4 may include a plurality of transistors such as a switching transistor, a driving transistor and a sensing transistor or the first to sixth transistors T1 to T6 as described later, a storage capacitor and a light emitting diode.

A structure of the display panel 140 and the subpixel SP of the display device 110 will be illustrated with reference to a drawing.

FIG. 2 is a cross-sectional view showing a display panel of a display device according to a first embodiment of the present disclosure.

In FIG. 2, the display panel 140 of the display device according to a first embodiment of the present disclosure includes first and second thin film transistors TFT1 and TFT2 and a storage capacitor CST. The first and second thin film transistors TFT1 and TFT2 may include a polycrystalline semiconductor material or an oxide semiconductor material. For example, the first thin film transistor TFT1 may include a polycrystalline semiconductor material, and the second thin film transistor TFT2 may include an oxide semiconductor material.

The first thin film transistor TFT1 is connected to a light emitting diode OLED, and the second thin film transistor is connected to the storage capacitor CST.

One pixel P includes the light emitting diode OLED and a pixel circuit supplying a driving current to the light emitting diode OLED. The pixel circuit is disposed on a substrate 211, and the light emitting diode OLED is disposed on the pixel circuit. An encapsulating layer 220 is disposed on the light emitting diode OLED to protect the light emitting diode OLED.

The pixel circuit may include a driving thin film transistor, a switching thin film transistor and a storage capacitor. The light emitting diode OLED may include an anode, a cathode and an emitting layer between the anode and the cathode.

The driving thin film transistor and at least one switching thin film transistor use an oxide semiconductor material as an active layer. The thin film transistor using the oxide semiconductor material as an active layer has an excellent blocking effect for a leakage current and has a lower fabrication cost as compared with a thin film transistor using a polycrystalline semiconductor material as an active layer. As a result, to reduce a power consumption and a fabrication cost, the pixel circuit may include the driving thin film transistor and the at least one switching thin film transistor using the oxide semiconductor material.

For example, all of thin film transistors of the pixel circuit may be formed of the oxide semiconductor material, or a portion of the switching thin film transistors may be formed of the oxide semiconductor material.

The thin film transistor using the oxide semiconductor material has a relatively low reliability, while the thin film transistor using the polycrystalline semiconductor material

has a relatively rapid operation speed and a relatively high reliability. As a result, the pixel circuit in an embodiment may include both of a switching thin film transistor using the oxide semiconductor material and a switching thin film transistor using the polycrystalline semiconductor material.

The substrate 211 may have multiple layers of an organic layer and an inorganic layer alternately laminated. For example, the substrate 211 may include an organic layer of an organic insulating material such as polyimide and an inorganic layer of an inorganic insulating material such as silicon oxide (SiO₂) alternately laminated.

A lower buffer layer 212a is disposed on the substrate 211. The lower buffer layer 212a may block a moisture permeable from an exterior and may have a multiple layer including silicon oxide (SiO₂). An auxiliary buffer layer 212b for protecting elements from a moisture is disposed on the lower buffer layer 212a.

The first thin film transistor TFT1 is disposed on the substrate 211. The first thin film transistor TFT1 may use a polycrystalline semiconductor material as an active layer. The first thin film transistor TFT1 includes a first active layer ACT1 having a channel where an electron or a hole moves, a first gate electrode GE1, a first source electrode SE1 and a first drain electrode DE1.

The first active layer ACT1 includes a first channel region, a first source region at one side of the channel region and a first drain region at the other side of the channel region.

The first source region and the first drain region includes an intrinsic polycrystalline semiconductor material doped with an impurity of III or V group such as boron (B) or phosphorous (P). The first channel region includes an intrinsic polycrystalline semiconductor material to provide a path where an electron or a hole moves.

The first thin film transistor TFT1 includes a first gate electrode GE1 overlapping the first channel region of the first active layer ACT1. A first gate insulating layer 213 is disposed between the first gate electrode GE1 and the first active layer ACT1. The first gate insulating layer 213 may have a single layer or a multiple layer of an inorganic insulating material such as silicon oxide (SiO₂) and silicon nitride (SiNx).

The first thin film transistor TFT1 has a top gate structure where the first gate electrode GE1 is disposed on the first active layer ACT1. As a result, a first capacitor electrode CST1 of the storage capacitor CST and a light shielding layer LS of the second thin film transistor TFT2 may have the same material as the first gate electrode GE1. A fabrication process may be simplified by forming the first gate electrode GE1, the first capacitor electrode CST1 and the light shielding layer LS through one mask process.

The first gate electrode GE1 may include a metallic material. For example, the first gate electrode GE1 may have a single layer or a multiple layer of one of molybdenum (Mo), aluminum (Al), chromium (Cr), gold (Au), titanium (Ti), nickel (Ni), neodymium (Nd), copper (Cu) and an alloy thereof.

A first interlayer insulating layer 214 is disposed on the first gate electrode GE1. The first interlayer insulating layer 214 may include an inorganic insulating material such as silicon oxide (SiO₂) and silicon nitride (SiNx).

The display panel 140 may further include an upper buffer layer 215, a second gate insulating layer 216 and a second interlayer insulating layer 217 sequentially disposed on the first interlayer insulating layer 214. The first thin film transistor TFT1 may include a first source electrode SE1 and a first drain electrode DE1 on the second interlayer insulating layer 217, and the first source electrode SE1 and the first

drain electrode DE1 may be connected to the first source region and the first drain region, respectively.

The first source electrode SE1 and the first drain electrode DE1 may have a single layer or multiple layers of one of molybdenum (Mo), aluminum (Al), chromium (Cr), gold (Au), titanium (Ti), nickel (Ni), neodymium (Nd), copper (Cu) and an alloy thereof.

The upper buffer layer 215 separates a second active layer ACT2 of an oxide semiconductor material of the second thin film transistor TFT2 from the first active layer ACT1 of a polycrystalline semiconductor material and provides a base for the second active layer ACT2.

The second gate insulating layer 216 covers the second active layer ACT2 of the second thin film transistor TFT2. Since the second gate insulating layer 216 is disposed on the second active layer ACT2 of an oxide semiconductor material, the second gate insulating layer 216 includes an inorganic insulating material. For example, the second gate insulating layer 216 may include silicon oxide (SiO₂) and silicon nitride (SiNx).

A second gate electrode GE2 includes a metallic material. For example, the second gate electrode GE2 may have a single layer or multiple layers of one of molybdenum (Mo), aluminum (Al), chromium (Cr), gold (Au), titanium (Ti), nickel (Ni), neodymium (Nd), copper (Cu) and an alloy thereof.

The second thin film transistor TFT2 is disposed on the upper buffer layer 215 and includes the second active layer ACT2 of an oxide semiconductor material, the second gate electrode GE2 on the second gate insulating layer 216, a second source electrode SE2 and a second drain electrode DE2 on the second interlayer insulating layer 217.

The second active layer ACT2 includes a second channel region, a second source region and a second drain region. The second channel region includes an intrinsic oxide semiconductor material which is not doped with an impurity, and the second source region and the second drain region are doped with an impurity to be conductorized.

The second thin film transistor TFT2 is disposed under the upper buffer layer 215 and further includes a light shielding layer LS overlapping the second active layer ACT2. The light shielding layer LS blocks a light incident to the second active layer ACT2 to obtain a reliability of the second thin film transistor TFT2. The light shielding layer LS may include the same material as the first gate electrode GE1 and may be disposed on a top surface of the first gate insulating layer 213. The light shielding layer LS may be electrically connected to the second gate electrode GE2 to constitute a double gate structure.

A fabrication process may be simplified by forming the second source electrode SE2 and the second drain electrode DE2 on the second interlayer insulating layer 217 simultaneously with the first source electrode SE1 and the first drain electrode DE1 through one mask process.

A second capacitor electrode CST2 is disposed on the first interlayer insulating layer 214. The second capacitor electrode CST2 overlaps the first capacitor electrode CST1 to constitute a storage capacitor CST. For example, the second capacitor electrode CST2 may have a single layer or a multiple layer of one of molybdenum (Mo), aluminum (Al), chromium (Cr), gold (Au), titanium (Ti), nickel (Ni), neodymium (Nd), copper (Cu) and an alloy thereof.

The storage capacitor CST stores the data signal supplied through the data line DL and supplies the data signal to the light emitting diode OLED. The storage capacitor CST includes two electrodes corresponding to each other and a dielectric layer between the two electrodes. A first interlayer

insulating layer 214 is disposed between the first capacitor electrode CST1 and the second capacitor electrode CST2.

One of the first and second capacitor electrodes CST1 and CST2 of the storage capacitor CST may be electrically connected to one of the second source electrode SE2 and the second drain electrode DE2 of the second thin film transistor TFT2. In another embodiment, a connection of the storage capacitor CST may be changed according to the pixel circuit.

A first planarizing layer 218 and a second planarizing layer 219 are sequentially disposed on the pixel circuit for planarizing the pixel circuit. The first planarizing layer 218 and the second planarizing layer 219 may include an organic insulating material such as polyimide and acrylic resin.

A light emitting diode OLED is disposed on the second planarizing layer 219.

The light emitting diode OLED includes an anode ANO, a cathode CAT and an emitting layer EL between the anode ANO and the cathode CAT. When the pixel circuit uses a low level voltage Vss (of FIG. 5) connected to the cathode CAT commonly, the anode ANO may be disposed in each subpixel as an individual electrode. When the pixel circuit uses a high level voltage connected to the anode ANO commonly, the cathode CAT may be disposed in each subpixel as an individual electrode.

The light emitting diode OLED is electrically connected to a driving element through a central electrode CNE on the first planarizing layer 218. The anode ANO of the light emitting diode OLED and the first source electrode SE1 of the first thin film transistor TFT1 of the pixel circuit are connected to each other through the central electrode CNE.

The anode ANO is connected to the central electrode CNE through a contact hole in the second planarizing layer 219. The central electrode CNE is connected to the first source electrode SE1 through a contact hole in the first planarizing layer 218.

The central electrode CNE connects the first source electrode SE1 and the anode ANO. The central electrode CNE may include a conductive material such as copper (Cu), silver (Ag), molybdenum (Mo) and titanium (Ti).

The anode ANO may have multiple layers including a transparent conductive layer and an opaque conductive layer having an excellent reflectance. The transparent conductive layer may include a material having a relatively high work function such as indium tin oxide (ITO) and indium zinc oxide (IZO). The opaque conductive layer may have a single layer or a multiple layer of one of aluminum (Al), silver (Ag), copper (Cu), lead (Pb), molybdenum (Mo), titanium (Ti) and an alloy thereof. For example, the anode ANO may have a structure such that a transparent conductive layer, an opaque conductive layer and a transparent conductive layer are sequentially laminated or a structure such that a transparent conductive layer and an opaque conductive layer are sequentially laminated.

The emitting layer EL includes a hole relating layer, an organic emitting layer and an electron relating layer sequentially or reversely laminated.

A bank layer BNK may be referred to as a pixel defining layer exposing the anode ANO of each subpixel SP1 to SP4. The bank layer BNK may include an opaque material (e.g., a black material) to prevent a light interference between the adjacent subpixels SP1 to SP4. The bank layer BNK may include a shielding material of at least one of a color pigment, an organic black and a carbon. A spacer may be disposed on the bank layer BNK.

The cathode CAT is disposed on a top surface and a side surface of the emitting layer EL to oppose the anode ANO

with the emitting layer interposed therebetween. The cathode CAT may be disposed in the entire display area DA as one body. In a top emission type display device, the cathode CAT may include a transparent conductive material such as indium tin oxide (ITO) and indium zinc oxide (IZO).

An encapsulating layer 220 that prevents or at least reduces permeation of a moisture may be disposed on the cathode CAT.

The encapsulating layer 220 may block permeation of a moisture or an oxygen of an exterior into the emitting layer EL. The encapsulating layer 220 may include at least one inorganic encapsulating layer and at least one organic encapsulating layer. The encapsulating layer 220 may exemplarily include a first encapsulating layer 221, a second encapsulating layer 222 and a third encapsulating layer 223 in the display device 110.

The first encapsulating layer 221 is disposed on the substrate 211 having the cathode CAT. The third encapsulating layer 223 is disposed on the substrate 211 having the second encapsulating layer 222 and wraps a top surface, a bottom surface and a side surface of the second encapsulating layer 222 with the first encapsulating layer 221. The first encapsulating layer 221 and the third encapsulating layer 223 may minimize or prevent permeation of a moisture or an oxygen of an exterior into the emitting layer EL. The first encapsulating layer 221 and the third encapsulating layer 223 may include an inorganic insulating material applicable to a low temperature deposition such as silicon nitride (SiNx), silicon oxide (SiOx), silicon oxynitride (SiON) and silicon aluminum oxide (Al2O3). Deterioration of the emitting layer EL vulnerable to a relatively high temperature may be prevented by depositing the first encapsulating layer 221 and the third encapsulating layer 223 under a relatively low temperature.

The second encapsulating layer 222 may alleviate a stress between the layers of the display device 110 due to bending and may planarize a step difference of the layers of the display device 110. The second encapsulating layer 222 may be disposed on the substrate 211 having the first encapsulating layer 221 and may include a non-photosensitive organic insulating material such as acrylic resin, epoxy resin, phenolic resin, polyamide resin, polyimide resin, polyethylene and silicon oxycarbide (SiOC) or a photosensitive organic insulating material such as photoacryl. When the second encapsulating layer 222 is formed through an inkjet method, a dam DAM may be disposed to prevent diffusion of the liquid material for the second encapsulating layer 222 to an edge portion of the substrate 211. The dam DAM may be disposed closer to the edge portion of the substrate 211 than the second encapsulating layer 222. Due to the dam DAM, it is prevented that the second encapsulating layer 222 is diffused to a pad area of an outermost edge portion of the substrate 211 where a conductive pad is disposed.

Although the dam DAM is disposed to prevent or at least reduce diffusion of the second encapsulating layer 222, moisture may permeate the emitting layer through the exposed second encapsulating layer 222 when the second encapsulating layer 222 is formed higher than the dam DAM. As a result, the dam DAM may be formed to have a number of at least ten.

The dam DAM may be disposed on the second interlayer insulating layer 217 in the non-display area NDA.

The dam DAM may be formed simultaneously with the first planarizing layer 218 and the second planarizing layer 219. For example, a lower layer of the dam DAM may be formed simultaneously with the first planarizing layer 218

and an upper layer of the dam DAM may be formed simultaneously with the second planarizing layer 219 such that the dam DAM has a double layered structure.

As a result, the dam DAM may have the same material as the first planarizing layer 218 and the second planarizing layer 219.

The dam DAM may be disposed to overlap a low level voltage line VSS. For example, the low level voltage line VSS may be disposed under the dam DAM in the non-display area NDA.

The low level voltage line VSS and the first and second gate driving units 130 and 135 having a gate-in-panel (GIP) type are disposed to surround the display area DA of the display panel 140, and the low level voltage line VSS may be disposed outside the first and second gate driving units 130 and 135. Further, the low level voltage line VSS may be connected to the cathode CAT to supply a common voltage. Although the first and second gate driving units 130 and 135 are shown to have a simple structure in FIG. 1, the first and second gate driving units 130 and 135 may include thin film transistors having the same structure as the thin film transistor of the display area DA.

For example, the low level voltage line VSS may have the same material as the first gate electrode GE1 or the same material as the second capacitor electrode CST2, the first source electrode SE1 and the first drain electrode DE1.

The low level voltage line VSS may supply a low level voltage Vss (of FIG. 5) to the subpixel SP1 to SP4 in the display area DA.

A touch layer may be disposed on the encapsulating layer 220. A touch buffer layer 251 of the touch layer may be disposed between a touch sensor metal and the cathode CAT of the light emitting diode OLED, and the touch sensor metal may include touch connecting lines 252 and 254 and touch electrodes 255 and 256.

The touch buffer layer 251 may block permeation of a solution (a developing solution or an etching solution) used in a fabrication process of the touch sensor metal on the touch buffer layer 251 or a moisture of an exterior into the emitting layer EL including an organic material. As a result, the touch buffer layer 251 may prevent deterioration of the emitting layer EL susceptible to a solution or a moisture.

The touch buffer layer 251 includes an organic insulating material applicable to a relatively low temperature lower than about 100° C. and having a dielectric constant of about 1 to about 3 to prevent deterioration of the emitting layer EL including an organic material vulnerable to a relatively high temperature. For example, the touch buffer layer 251 may include a material of an acrylic group, an epoxy group or a siloxane group. The touch buffer layer 251 of an organic insulating material having a planarization property may prevent deterioration of the encapsulating layer 220 due to a bending of the display device 110 and a breakdown of the touch sensor metal on the touch buffer layer 251.

In a touch sensor structure based on a mutual capacitance, the touch electrodes 255 and 256 may be disposed on the touch buffer layer 251 and may alternate each other.

The touch connecting lines 252 and 254 may connect the touch electrodes 255 and 256 electrically. The touch connecting lines 252 and 254 and the touch electrodes 255 and 256 may be disposed in different layers, and a touch insulating layer 253 may be disposed between the touch connecting lines 252 and 254 and the touch electrodes 255 and 256.

The touch connecting lines 252 and 254 may be disposed to overlap the bank layer BNK to prevent reduction of an aperture ratio.

The touch electrodes 255 and 256 may be electrically connected to a touch driving circuit (not shown) through a portion of the touch connecting line 252 passing through a top surface and a side surface of the encapsulating layer 220 and a top surface and a side surface of the dam DAM and connected to a touch pad PAD.

The portion of the touch connecting line 252 may receive a touch driving signal from the touch driving circuit and may transmit the touch driving signal to the touch electrodes 255 and 256. The portion of the touch connecting line 252 may transmit a touch sensing signal of the touch electrodes 255 and 256 to the touch driving circuit.

A touch protecting layer 257 may be disposed on the touch electrodes 255 and 256. Although the touch protecting layer 257 is disposed on the touch electrodes 255 and 256 in an embodiment of FIG. 2, the touch protecting layer 257 may extend a front or a rear of the dam DAM to be disposed on the touch connecting line 252.

A color filter (not shown) may be disposed on the encapsulating layer 220. The color filter may be disposed on the touch layer or may be disposed between the encapsulating layer 220 and the touch layer.

A structure and an operation of the first and second gate driving units and the first, second, third and fourth subpixels SP1, SP2, SP3 and SP4 of the display device 110 will be illustrated with reference to a drawing.

FIG. 3 is a block diagram showing first and second gate driving units and a display panel of a display device according to a first embodiment of the present disclosure, FIG. 4 is a block diagram showing first and second gate driving units and a display panel of a display device according to a second embodiment of the present disclosure, and FIG. 5 is a circuit diagram showing a subpixel of a display device according to a first embodiment of the present disclosure.

In FIG. 3, the first gate driving unit 130 of the display device 110 according to a first embodiment of the present disclosure includes a gate1 signal block Bsc1 and a gate2 signal block Bsc2, and the second gate driving unit 135 of the display device 110 according to a first embodiment of the present disclosure includes an emission1 signal block Bem1 and an emission2 signal block Bem2. The display area DA of the display panel 140 is disposed between the first and second gate driving units 130 and 135.

In a first embodiment of FIG. 3, the gate1 signal block Bsc1 is disposed farther from the display panel 140 than the gate2 signal block Bsc2 and the emission1 signal block Bem1 is disposed farther from the display panel 140 than the emission2 signal block Bem2. In another embodiment, the gate2 signal block Bsc2 may be disposed farther from the display panel 140 than the gate1 signal block Bsc1 and the emission2 signal block Bem2 may be disposed farther from the display panel 140 than the emission1 signal block Bem1.

Each of the gate1 signal block Bsc1 and the gate2 signal block Bsc2 of the first gate driving unit 130 and the emission1 signal block Bem1 and the emission2 signal block Bem2 of the second gate driving unit 135 may be one stage of a shift register, and the shift register may include a plurality of stages connected to each other in a cascade type.

In the first gate driving unit 130, the gate1 signal block Bsc1 generates a gate1 signal Sc1 (of FIG. 5), and the gate2 signal block Bsc2 generates a gate2 signal Sc2 (of FIG. 5).

In the second gate driving unit 135, the emission1 signal block Bem1 generates an emission1 signal Em1 (of FIG. 5), and the emission2 signal block Bem2 generates an emission2 signal Em2 (of FIG. 5).

The gate1 signal Sc1 of the gate1 signal block Bsc1 is supplied to third and sixth transistors T3 and T6 (of FIG. 5)

in each subpixel SP1 to SP4 of the display area DA through the gate line GL. The gate2 signal Sc2 of the gate2 signal block Bsc2 is supplied to a first transistor T1 (of FIG. 5) in each subpixel SP1 to SP4 of the display area DA through the gate line GL.

The emission1 signal Em1 of the emission1 signal block Bem1 is supplied to a fifth transistor T5 (of FIG. 5) in each subpixel SP1 to SP4 of the display area DA through the gate line GL. The emission2 signal Em2 of the emission2 signal block Bem2 is supplied to a fourth transistor T4 (of FIG. 5) in each subpixel SP1 to SP4 of the display area DA through the gate line GL.

In another embodiment, the structure of the gate1 signal block Bsc1, the gate2 signal block Bsc2, the emission1 signal block Bem1 and the emission2 signal block Bem2 may be variously changed in the first and second gate driving units 130 and 135.

In FIG. 4, a first gate driving unit 230 of a display device according to a second embodiment of the present disclosure includes a gate1 signal block Bsc1 and an emission1 signal block Bem1, and a second gate driving unit 235 of the display device according to a second embodiment of the present disclosure includes a gate2 signal block Bsc2 and an emission2 signal block Bem2. A display area DA of a display panel 240 is disposed between the first and second gate driving units 230 and 235.

In a second embodiment of FIG. 4, the gate1 signal block Bsc1 is disposed farther from the display panel 240 than the emission1 signal block Bem1 and the gate2 signal block Bsc2 is disposed farther from the display panel 240 than the emission2 signal block Bem2. In another embodiment, the emission1 signal block Bem1 may be disposed farther from the display panel 240 than the gate1 signal block Bsc1 and the emission2 signal block Bem2 may be disposed farther from the display panel 240 than the gate2 signal block Bsc2.

In another embodiment, the first and second gate driving units 130 and 135 may have a symmetrical structure. For example, each of the first and second gate driving units 130 and 135 may include the gate1 signal block Bsc1, the gate2 signal block Bsc2, the emission1 signal block Bem1 and the emission2 signal block Bem2.

In FIG. 5, each of the first to fourth subpixels SP1 to SP4 of the display panel 140 of the display device 110 according to a first embodiment of the present disclosure includes first to sixth transistors T1 to T6, a storage capacitor Cs and a light emitting diode De. At least one of the first to sixth transistors T1 to T6 may be an oxide semiconductor thin film transistor, and the others of the first to sixth transistors T1 to T6 may be a low temperature polycrystalline silicon thin film transistor.

For example, the second, third, fourth and fifth transistors T2, T3, T4 and T5 may be a negative (N) type low temperature polycrystalline silicon thin film transistor, and the first and sixth transistors T1 and T6 may be a negative (N) type oxide semiconductor thin film transistor.

The first transistor T1 is a switching transistor and is switched according to a gate2 signal Sc2. A gate electrode of the first transistor T1 is connected to the gate2 signal Sc2, a source electrode of the first transistor T1 is connected to a source electrode of the second transistor T2 and a drain electrode of the fifth transistor T5, and a drain electrode of the first transistor T1 is connected to the data signal Vdata, a stress signal Vobs and an anode reset signal Var.

The second transistor T2 is a driving transistor and is switched according to a voltage of a first capacitor electrode of the storage capacitor Cs. A gate electrode of the second transistor T2 is connected to the first capacitor electrode of

the storage capacitor Cs and a drain electrode of the third transistor T3, a source electrode of the second transistor T2 is connected to a source electrode of the first transistor T1 and a drain electrode of the fifth transistor T5, and a drain electrode of the second transistor T2 is connected to a source electrode of the third transistor T3 and a source electrode of the fourth transistor T4.

The third transistor T3 is a sensing transistor and is switched according to a gate1 signal Sc1. A gate electrode of the third transistor T3 is connected to the gate1 signal Sc1, a source electrode of the third transistor T3 is connected to a drain electrode of the second transistor T2, and a drain electrode of the third transistor T3 is connected to a gate electrode of the second transistor T2 and a first capacitor electrode of the storage capacitor Cs.

The fourth transistor T4 is an emission transistor and is switched according to an emission2 signal Em2. A gate electrode of the fourth transistor T4 is connected to the emission2 signal Em2, a source electrode of the fourth transistor T4 is connected to a drain electrode of the second transistor T2 and a source electrode of the third transistor T3, and a drain electrode of the fourth transistor T4 is connected to a high level signal Vdd.

The fifth transistor T5 is an emission transistor and is switched according to an emission1 signal Em1. A gate electrode of the fifth transistor T5 is connected to the emission1 signal Em1, a source electrode of the fifth transistor T5 is connected to an anode of the light emitting diode De, a source electrode of the sixth transistor T6 and a second capacitor electrode of the storage capacitor Cs, and a drain electrode of the fifth transistor T5 is connected to a source electrode of the first transistor T1 and a source electrode of the second transistor T2.

The sixth transistor T6 is an initialization transistor and is switched according to the gate1 signal Sc1. A gate electrode of the sixth transistor T6 is connected to the gate1 signal Sc1, a source electrode of the sixth transistor T6 is connected to a source electrode of the fifth transistor T5, an anode of the light emitting diode De and a second capacitor electrode of the storage capacitor Cs, and a drain electrode of the sixth transistor T6 is connected to an initial voltage Vini.

The storage capacitor Cs stores the data signal Vdata and the threshold voltage Vth. A first capacitor electrode of the storage capacitor Cs is connected to the gate electrode of the second transistor T2 and the drain electrode of the third transistor T3, and a second capacitor electrode of the storage capacitor Cs is connected to the source electrode of the fifth transistor T5, the source electrode of the sixth transistor T6 and the anode of the light emitting diode De.

The light emitting diode De is connected between the fifth and sixth transistors T5 and T6 and the low level signal Vss to emit a light of a luminance proportional to a current of the second transistor T2. An anode of the light emitting diode De is connected to the source electrode of the fifth transistor T5, the source electrode of the sixth transistor T6 and the second capacitor electrode of the storage capacitor Cs, and a cathode of the light emitting diode De is connected to the low level signal Vss.

The drain electrode of the second transistor T2, the source electrode of the third transistor T3 and the source electrode of the fourth transistor T4 constitute a first node N1, and the gate electrode of the second transistor T2, the drain electrode of the third transistor T3 and the first capacitor electrode of the storage capacitor Cs constitute a second node N2. The source electrode of the first transistor T1, the source electrode of the second transistor T2 and the drain electrode of the fifth transistor T5 constitute a third node N3, and the

source electrode of the fifth transistor T₅, the source electrode of the sixth transistor T₆, the second capacitor electrode of the storage capacitor C_s and the anode of the light emitting diode D_e constitute a fourth node N₄.

The data signal V_{data}, the stress signal V_{obs} and the anode reset signal V_{ar} are supplied to each of the first to fourth subpixels SP₁ to SP₄ of the display panel 140 from the data driving unit 125, and the gate1 signal Sc₁, the gate2 signal Sc₂, the emission1 signal Em₁ and the emission2 signal Em₂ are supplied to each of the first to fourth subpixels SP₁ to SP₄ of the display panel 140 from the first and second gate driving units 130 and 135.

When the display device 110 is driven with a relatively low frequency, one frame may be classified into a refresh subframe and a holding subframe.

FIG. 6 is a view showing a plurality of signals in a refresh subframe of a display device according to a first embodiment of the present disclosure, and FIG. 7 is a view showing a plurality of signals in a holding subframe of a display device according to a first embodiment of the present disclosure.

When the display device 110 according to a first embodiment of the present disclosure is driven with a relatively low frequency such as about 1 Hz, the display panel 140 in the display device 110 displays the image during a plurality of frames, a single frame is classified into a refresh subframe SF_{rf} where the data signal V_{data} is inputted and a light corresponding to the data signal V_{data} is emitted and a holding subframe SF_{hd} where a light corresponding to the data signal V_{data} inputted in the refresh subframe SF_{rf} without an input of a new data signal V_{data}. During the holding subframe SF_{hd}, the stress signal V_{obs} is applied to the second transistor T₂ of a driving transistor, and the anode reset signal V_{ar} is applied to the light emitting diode D_e.

For example, when a single frame includes 1st to 60th subframes, the 1st subframe may be used as the refresh subframe SF_{rf}, and the 2nd to 60th subframes may be used as the holding subframe SF_{hd}.

In FIG. 6, during a first period TP₁ of a sampling period of the refresh subframe SF_{rf} of the display device 110 according to a first embodiment of the present disclosure, the gate1 signal Sc₁ and the gate2 signal Sc₂ have a logic high voltage V_h, and the emission1 signal Em₁ and the emission2 signal Em₂ have a logic low voltage V_l that is less than the logic high voltage V_h.

As a result, the first, third and sixth transistors T₁, T₃ and T₆ are turned on, and the fourth and fifth transistors T₄ and T₅ are turned off. Further, the data signal V_{data} is applied to the third, first and second nodes N₃, N₁ and N₂ (the gate electrode of the second transistor T₂) through the first, second and third transistors T₁, T₂ and T₃, and the initial voltage V_{ini} is applied to the fourth node N₄ (the anode of the light emitting diode D_e) through the sixth transistor T₆.

During the first period TP₁, since a sum of the data signal V_{data} and the threshold voltage V_{th} of the second transistor T₂ is applied to the second node N₂, compensation for the threshold voltage of the second transistor T₂ is performed. Further, since the initial voltage V_{ini} is applied to the anode of the light emitting diode D_e, the anode of the light emitting diode D_e is initialized.

During a second period TP₂ of a stress period of the refresh subframe SF_{rf}, the gate1 signal Sc₁, the emission1 signal Em₁ and the emission2 signal Em₂ have a logic low voltage V_l, and the gate2 signal Sc₂ has a logic high voltage V_h.

As a result, the first transistor T₁ is turned on, and the third, fourth, fifth and sixth transistors T₃, T₄, T₅ and T₆ are

turned off. Further, the stress signal V_{obs} is applied to the third node N₃ (the source electrode of the second transistor T₂) through the first transistor T₁.

During the second period TP₂, since the third node N₃ is reset, a hysteresis of the second transistor T₂ such as a variation of the threshold voltage V_{th} of the second transistor T₂ is prevented.

During a third period TP₃ of an emission period of the refresh subframe SF_{rf}, the gate1 signal Sc₁ and the gate2 signal Sc₂ have a logic low voltage V_l, and the emission1 signal Em₁ and the emission2 signal Em₂ have a logic high voltage V_h.

As a result, the first, third and sixth transistors T₁, T₃ and T₆ are turned off, and the fourth and fifth transistors T₄ and T₅ are turned on. Further, the high level signal V_{dd} is applied to the first, third and fourth nodes N₁, N₃ and N₄ (the anode of the light emitting diode D_e) through the fourth, second and fifth transistors T₄, T₂ and T₅. A current corresponding to the data signal V_{data} where the threshold voltage V_{th} is compensated flows in the second transistor T₂ which is turned on.

During the third period TP₃, the light emitting diode D_e emits a light corresponding to the inputted data signal V_{data}.

In FIG. 7, during a fourth period TP₄ of a stress period of the holding subframe SF_{hd} of the display device 110 according to a first embodiment of the present disclosure, the gate1 signal Sc₁, the emission1 signal Em₁ and the emission2 signal Em₂ have a logic low voltage V_l, and the gate2 signal Sc₂ has a logic high voltage V_h.

Here, the fourth period TP₄ may be defined as an interval between a rising timing of the gate2 signal Sc₂ and a rising timing of the emission1 signal Em₁.

As a result, the first transistor T₁ is turned on, and the third, fourth, fifth and sixth transistors T₃, T₄, T₅ and T₆ are turned off. Further, the stress signal V_{obs} is applied to the third node N₃ (the source electrode of the second transistor T₂) through the first transistor T₁.

During the fourth period TP₄, since the third node N₃ is reset, a hysteresis of the second transistor T₂ such as a variation of the threshold voltage V_{th} of the second transistor T₂ is prevented.

During a fifth period TP₅ of an anode reset period of the holding subframe SF_{hd}, the gate1 signal Sc₁ and the emission2 signal Em₂ have a logic low voltage V_l, and the gate2 signal Sc₂ and the emission1 signal Em₁ have a logic high voltage V_h.

As a result, the first and fifth transistors T₁ and T₅ are turned on, and the third, fourth and sixth transistors T₃, T₄ and T₆ are turned off. Further, the anode reset signal V_{ar} is applied to the fourth node N₄ through the first and fifth transistors T₁ and T₅.

During the fifth period TP₅, since the fourth node N₄ is reset, a hysteresis of the light emitting diode D_e due to a voltage of the fourth node N₄ of a previous frame is prevented.

During a sixth period TP₆ of an emission period of the holding subframe SF_{hd}, the gate1 signal Sc₁ and the gate2 signal Sc₂ have a logic low voltage V_l, and the emission1 signal Em₁ and the emission2 signal Em₂ have a logic high voltage V_h.

As a result, the first, third and sixth transistors T₁, T₃ and T₆ are turned off, and the fourth and fifth transistors T₄ and T₅ are turned on. Further, the high level signal V_{dd} is applied to the first, third and fourth nodes N₁, N₃ and N₄ (the anode of the light emitting diode D_e) through the fourth, second and fifth transistors T₄, T₂ and T₅. A current

corresponding to the data signal V_{data} which is inputted during the refresh subframe SF_{rf} flows in the second transistor T_2 which is turned on.

During the sixth period TP_6 , the light emitting diode D_E emits a light corresponding to the data signal V_{data} which is inputted during the refresh subframe SF_{rf} .

In the display device **110** according to a first embodiment of the present disclosure, during the fourth period TP_4 of the stress period of the holding subframe SF_{hd} , since the stress signal V_{obs} is applied to the third node N_3 , a hysteresis of the second transistor T_2 of the driving transistor is improved.

Here, a display brightness value of an image is divided into a plurality of luminance bands, and the plurality of luminance bands have different flicker properties. For the plurality of luminance bands having a similar flicker property or an identical flicker property, the plurality of luminance bands are displayed using one of a plurality of high level signals V_{dd} having different high level voltages and a corresponding one of stress signal V_{obs} having different parking voltages.

Since the high level signal V_{dd} of the different high level voltage for the luminance band and the stress signal V_{obs} of the different parking voltage for the luminance band are used, a uniformity of a flicker property is improved and a variable frequency driving property is improved.

For example, one of the first to fifth luminance bands may be displayed by supplying one corresponding high level voltage of first to fifth high level voltages of about 9.0V, about 7.0V, about 6.5V, about 6.0V and about 5.5V, respectively, as the high level signal V_{dd} to the fourth transistor T_4 , and first to fifth parking voltages V_{p1} to V_{p5} different from each other as the stress signal V_{obs} corresponding to the corresponding high level voltage may be applied to the third node N_3 (the source electrode of the second transistor T_2) for the high level signal V_{dd} of the first to fifth high level voltages, respectively, during the fourth period TP_4 as the stress period.

Here, deterioration such as a flicker may be reduced or minimized by changing (determining) a width of the fourth period TP_4 of the stress period according to the luminance band of an image, and a display quality may be improved. Particularly, the width of the fourth period TP_4 may be changed (determined) according to the high level signal V_{dd} and the stress signal V_{obs} .

For example, as shown in FIG. 7, the fourth period TP_4 as the stress period is determined to have one of first to n th widths w_1 to w_n according to the luminance band, or according to the high level signal V_{dd} and the stress signal V_{obs} . Thereby, deterioration such as a flicker is reduced or minimized and a display quality is improved.

For example, the first width w_1 may be about 5.5 horizontal periods (5.5H), the second width w_2 may be about 3.5 horizontal period (3.5H), and the third width w_3 may be about 2.5 horizontal period (2.5H). One horizontal period (1H) may be an interval where the data signal V_{data} is supplied to the subpixels in one horizontal pixel line.

Accordingly, in a display device **110** according to a first embodiment of the present disclosure, the display panel **140** may display the image using one of a plurality of high level voltages according to the luminance band. The data driving unit **125** may supply one of a plurality of parking voltages V_p corresponding to one high level voltage during the fourth period TP_4 . The timing controlling unit may determine the width of the fourth period TP_4 according to the supplied parking voltage.

A method of changing a width of the stress period will be illustrated with reference to a drawing.

FIG. 8 is a flow chart showing a method of driving a display device according to a first embodiment of the present disclosure.

In FIG. 8, after the display device **110** according to a first embodiment of the present disclosure displays an image during a previous frame, the timing controlling unit **120** calculates a luminance band of a present frame and verifies a change from the luminance band of the previous frame to the luminance band of the present frame. (st110)

For example, the timing controlling unit **120** determines that the luminance has been changed from the luminance band of the previous frame to the luminance band of the present frame, by calculating the luminance band of the present frame. For example, the first luminance band of the previous frame may be changed to the second luminance band of the present frame.

Next, the timing controlling unit **120** starts a variable stress period mode where a width of the fourth period TP_4 as the stress period of the holding subframe SF_{hd} may be changed. (st112)

Next, the timing controlling unit **120** changes the high level signal V_{dd} to correspond to the luminance band of the present frame. (st114)

For example, a first high level signal having the first high level voltage of about 9.0V of the previous frame may be changed to the second high level voltage of about 7.0V of the present frame.

Next, the timing controlling unit **120** judges whether a previous stress signal V_{obs} corresponding to the luminance band of the previous frame is identical (e.g., equal) to a present stress signal V_{obs} corresponding to the luminance band of the present frame or not with reference to a lookup table (LUT). (st116)

When the previous stress signal V_{obs} is not identical to the present stress signal V_{obs} (no), the timing controlling unit **120** updates the stress signal V_{obs} with reference to the lookup table. (st118)

Here, the lookup table may store a correspondence relation of the plurality of luminance bands and the plurality of parking voltages.

For example, when the lookup table stores that the previous stress signal V_{obs} corresponding to the first luminance band of the previous frame is the first parking voltage V_{p1} and the present stress signal V_{obs} corresponding to the second luminance band of the present frame is the second parking voltage V_{p2} , the timing controlling unit **120** may update the stress signal V_{obs} from the first parking voltage V_{p1} to the second parking voltage V_{p2} .

When the previous stress signal V_{obs} is identical to the present stress signal V_{obs} (yes), the timing controlling unit **120** does not update the stress signal V_{obs} to maintain the previous stress signal V_{obs} as the present stress signal V_{obs} , and a step (st120) of comparing a previous stress period width and a present stress period width is performed.

Next, the timing controlling unit **120** judges whether a width of the fourth period TP_4 of the previous frame (a previous stress period) is identical to a width of the fourth period TP_4 of the present frame (a present stress period) or not with reference to a lookup table (LUT). (st120)

When the width of the previous stress period is not identical to the width of the present stress period (no), the timing controlling unit **120** updates the width of the stress period with reference to the lookup table. (st122)

Here, the lookup table may store a correspondence relation of the plurality of parking voltages and the width of the stress period.

For example, when the lookup table stores that the previous stress period TP4 corresponding to the first parking voltage Vp1 of the previous frame has the first width w1 and the present stress period TP4 corresponding to the second parking voltage Vp2 of the present frame has the second width w2, the timing controlling unit 120 may update the width of the stress period TP4 from the first width w1 to the second width w2.

When the width of the previous stress period TP4 is identical to the width of the present stress period TP4 (yes), the timing controlling unit 120 does not update the width of the stress period TP4 to maintain the width of the previous stress period TP4 as the width of the present stress period TP4, and a step (st124) of ending the variable stress period mode is performed.

Next, the timing controlling unit 120 finishes the variable stress period mode. (st124)

An operation in the variable stress period mode where the width of the fourth period TP4 of the stress period (the rising timing of the fourth period TP4) is changed according to the high level signal Vdd and the stress signal Vobs will be illustrated with reference to drawings.

FIG. 9 is a table showing a flicker index of a display device according to a first embodiment of the present disclosure, and FIG. 10 is a view showing a luminance change of a display device according to a first embodiment of the present disclosure.

In FIG. 9, the stress signal Vobs of the first, second, third, fourth and fifth parking voltages Vp1, Vp2, Vp3, Vp4 and Vp5 corresponding to the first, second, third, fourth and fifth high level voltages of about 9.0V, about 7.0V, about 6.5V, about 6.0V and about 5.5V, respectively, is applied to the third node N3 in a display device according to a first comparison example where the stress period TP4 has a fixed first width w1, and the display device according to a first comparison example has flicker indexes of about -6, about -6, about -4, about -3 and about 0, respectively.

The flicker index is an index according to a luminance waveform difference between the refresh subframe SFrf and the holding subframe SFhd when the display device is driven with a relatively low frequency such as about 1 Hz. As the flicker index decreases, occurrence of the flicker decreases.

The stress signal Vobs of the first, second, third, fourth and fifth parking voltages Vp1, Vp2, Vp3, Vp4 and Vp5 corresponding to the first, second, third, fourth and fifth high level voltages of about 9.0V, about 7.0V, about 6.5V, about 6.0V and about 5.5V, respectively, is applied to the third node N3 in a display device according to a second comparison example where the stress period TP4 has a fixed second width w2, and the display device according to a second comparison example has flicker indexes of about -4, about -5, about -5, about -7 and about -3, respectively.

The flicker index of the first comparison example corresponding to the first width w1 is lower than the flicker index of the second comparison example corresponding to the second width w2 for the first and second high level voltages of about 9.0V and about 7.0V and the first and second parking voltages Vp1 and Vp2, while the flicker index of the first comparison example corresponding to the first width w1 is higher than the flicker index of the second comparison example corresponding to the second width w2 for the third,

fourth and fifth high level voltages of about 6.5V, about 6.0V and about 5.5V and the third, fourth and fifth parking voltages Vp3, Vp4 and Vp5.

As a result, an effect of improving the flicker is reduced for the third, fourth and fifth high level voltages of about 6.5V, about 6.0V and about 5.5V and the third, fourth and fifth parking voltages Vp3, Vp4 and Vp5 in the first comparison example, while an effect of improving the flicker is reduced for the first and second high level voltages of about 9.0V and about 7.0V and the first and second parking voltages Vp1 and Vp2 in the second comparison example.

The stress signal Vobs of the first and second parking voltages Vp1 and Vp2 corresponding to the first and second high level voltages of about 9.0V and about 7.0V is applied to the third node N3 during the stress period TP4 of the first width w1 in the display device 110 according to a first embodiment of the present disclosure, and the display device 110 has flicker indexes of about -6 and about -6, respectively. Further, the stress signal Vobs of the third, fourth and fifth parking voltages Vp3, Vp4 and Vp5 corresponding to the third, fourth and fifth high level voltages of about 6.5V, about 6.0V and about 5.5V is applied to the third node N3 during the stress period TP4 of the second width w2 in the display device 110 according to a first embodiment of the present disclosure, and the display device 110 has flicker indexes of about -5, about -7 and about -3, respectively.

Since the width of the stress period TP4 is changed according to the high level signal Vdd and the stress signal Vobs in the display device 110 according to a first embodiment of the present disclosure, the display device 110 has a relatively low flicker index for all of luminance bands and deterioration such as a flicker is reduced or minimized.

For example, in FIG. 10, the stress signal Vobs of the first parking voltage Vp1 is applied to the third node N3 during the stress period TP4 of the first width w1 for the first high level voltage of about 9.0V, and the stress signal Vobs of the fourth parking voltage Vp4 is applied to the third node N3 during the stress period TP4 of the second width w2 different from the first width w1 for the fourth high level voltage of about 6.0V. As a result, both of a refresh-holding gap corresponding to the first width w1 and a refresh-holding gap corresponding to the second width w2 are reduced.

The refresh-holding gap may be defined as a difference between lowest luminances of the refresh subframe SFrf and the holding subframe SFhd.

In the display device 110 according to an embodiment of the present disclosure, a hysteresis of the second transistor of the driving transistor is improved by applying the stress signal Vobs to the third node N3 during the fourth period TP4 as the stress period of the holding subframe SFhd. Further, deterioration such as a flicker is reduced or minimized by changing the width of the fourth period TP4 of the stress period according to the high level signal Vdd and the stress signal Vobs.

Consequently, in the display device according to the present disclosure, since the width of the stress period where the stress signal is applied is changed according to the luminance band during the holding subframe of a relatively low frequency, deterioration such as a flicker is reduced or minimized and the display quality is improved.

Further, since the width of the stress period is changed according to the high level signal and the stress signal during the holding subframe of a relatively low frequency, a hysteresis of the driving transistor is improved and the flicker index is reduced or minimized due to reduction of the refresh-holding gap.

21

It will be apparent to those skilled in the art that various modifications and variation can be made in the present disclosure without departing from the scope of the disclosure. Thus, it is intended that the present disclosure cover the modifications and variations of this disclosure provided they come within the scope of the appended claims.

What is claimed is:

1. A display device, comprising:
    - a timing controlling circuit configured to generate an image data, a data control signal and a gate control signal;
    - a data driving circuit configured to generate a data signal, a stress signal, and an anode reset signal using the image data and the data control signal;
    - a gate driving circuit configured to generate a gate1 signal, a gate2 signal, an emission1 signal, and an emission2 signal using the gate control signal; and
    - a display panel configured to display an image using the data signal, the gate1 signal, the gate2 signal, the emission1 signal and the emission2 signal,
- wherein a width of a stress period between a rising timing of the gate2 signal and a rising timing of the emission1 signal is changed according to a luminance band of the image, and
- wherein the display panel includes a plurality of subpixels, each of the plurality of subpixels comprising:
- a storage capacitor;
  - a first transistor switched according to the gate2 signal, the first transistor connected to one of the data signal, the stress signal, and the anode reset signal;
  - a second transistor switched according to a voltage of a first capacitor electrode of the storage capacitor;
  - a third transistor switched according to the gate1 signal, the third transistor connected to the storage capacitor and the second transistor;
  - a fourth transistor switched according to the emission2 signal, the fourth transistor connected to a high level signal, the second transistor, and the third transistor;
  - a fifth transistor switched according to the emission1 signal, the fifth transistor connected to the first transistor and the second transistor;
  - a sixth transistor switched according to the gate1 signal, the sixth transistor connected to the storage capacitor, the fifth transistor, and an initial voltage; and
  - a light emitting diode connected between the fifth transistor, the sixth transistor, and a low level signal.
2. The display device of claim 1, wherein the display panel displays the image using one of a plurality of high level voltages according to the luminance band, wherein the data driving circuit is configured to supply one of a plurality of parking voltages corresponding to the plurality of high level voltages during the stress period, and wherein the timing controlling circuit is configured to determine the width of the stress period according to the plurality of parking voltages.
  3. The display device of claim 1, wherein the display panel displays the image during a plurality of frames, each of the plurality of frames comprising:
    - a refresh subframe where the data signal is inputted and a light corresponding to the data signal is emitted; and
    - a holding subframe where an input of the data signal is stopped and a light corresponding to the data signal inputted during the refresh subframe is emitted.
  4. The display device of claim 3, wherein during a first period of the refresh subframe, the data signal is applied to a gate electrode of the second transistor through the first

22

transistor, the second transistor, and the third transistor, and the initial voltage is applied to an anode of the light emitting diode through the sixth transistor,

wherein during a second period of the refresh subframe, the stress signal is applied to a source electrode of the second transistor through the first transistor, and

wherein during a third period of the refresh subframe, the high level signal is applied to the anode of the light emitting diode through the fourth transistor, the second transistor, and the fifth transistor.

5. The display device of claim 3, wherein during a fourth period of the holding subframe, the stress signal is applied to a source electrode of the second transistor through the first transistor,

wherein during a fifth period of the holding subframe, the anode reset signal is applied to an anode of the light emitting diode through the first transistor and the fifth transistor, and

wherein during a sixth period of the holding subframe, the high level signal is applied to the anode of the light emitting diode through the fourth transistor, the second transistor and the fifth transistor.

6. The display device of claim 1, wherein at least one of the first transistor to the sixth transistor is an oxide semiconductor thin film transistor.

7. The display device of claim 1, wherein one of a plurality of luminance bands is displayed by supplying a corresponding high level voltage of a plurality of high level voltages as the high level signal to the fourth transistor, and applying one of a plurality of parking voltages that is corresponding to the corresponding high level voltage as a stress signal to a source electrode of the second transistor during the stress period.

8. The display device of claim 7, wherein the stress period is determined to have one of a plurality of widths according to the high level signal and the stress signal.

9. The display device of claim 1, wherein the gate driving circuit includes a first gate driving circuit and a second gate driving circuit disposed at both sides of the display panel; wherein the first gate driving circuit includes a gate1 signal circuit generating the gate1 signal and a gate2 signal circuit generating the gate2 signal; and wherein the second gate driving circuit includes an emission1 signal circuit generating the emission1 signal and an emission2 signal circuit generating the emission2 signal.

10. The display device of claim 9, wherein the gate1 signal circuit is disposed farther from the display panel than the gate2 signal circuit, or the gate2 signal circuit is disposed farther from the display panel than the gate1 signal circuit, and

wherein the emission1 signal circuit is disposed farther from the display panel than the emission2 signal circuit, or the emission2 signal circuit is disposed farther from the display panel than the emission1 signal circuit.

11. The display device of claim 1, wherein the gate driving circuit includes a first gate driving circuit and a second gate driving circuit disposed at both sides of the display panel;

wherein the first gate driving circuit includes a gate1 signal circuit generating the gate1 signal and an emission1 signal circuit generating the emission1 signal; and

wherein the second gate driving circuit includes a gate2 signal circuit generating the gate2 signal and an emission2 signal circuit generating the emission2 signal.

23

12. The display device of claim 11, wherein the gate1 signal circuit is disposed farther from the display panel than the emission1 signal circuit, or the emission1 signal circuit is disposed farther from the display panel than the gate1 signal circuit, and

wherein the gate2 signal circuit is disposed farther from the display panel than the emission2 signal circuit, or the emission2 signal circuit is disposed farther from the display panel than the gate2 signal circuit.

13. The display device of claim 1, wherein the gate driving circuit includes a first gate driving circuit and a second gate driving circuit disposed at both sides of the display panel; and

wherein each of the first gate driving circuit and the second gate driving circuit includes a gate1 signal circuit generating the gate1 signal, a gate2 signal circuit generating the gate2 signal, an emission1 signal circuit generating the emission1 signal and an emission2 signal circuit generating the emission2 signal.

14. A method of driving a display device, comprising: generating an image data, a data control signal and a gate control signal;

generating a data signal, a stress signal and an anode reset signal using the image data and the data control signal;

generating a gate1 signal, a gate2 signal, an emission1 signal and an emission2 signal using the gate control signal; and

displaying an image using the data signal, the gate1 signal, the gate2 signal, the emission1 signal and the emission2 signal,

wherein a width of a stress period between a rising timing of the gate2 signal and a rising timing of the emission1 signal is determined according to a luminance band of the image, and

wherein changing the width of the stress period comprises:

verifying a change from the luminance band of a previous frame to the luminance band of a present frame;

changing a high level signal to correspond to the luminance band of the present frame;

judging whether a previous stress signal corresponding to the luminance band of the previous frame is identical to

24

a present stress signal corresponding to the luminance band of the present frame or not with reference to a lookup table;

updating the stress signal when the previous stress signal is not identical to the present stress signal;

maintaining the previous stress signal as the present stress signal when the previous stress signal is identical to the present stress signal;

judging whether a width of a previous stress period of the previous frame is identical to a width of a present stress period of the present frame or not with reference to the lookup table;

updating the width of the stress period when the width of the previous stress period is not identical to the width of the present stress period; and

maintaining the width of the previous stress period as the width of the present stress period when the width of the previous stress period is identical to the width of the present stress period.

15. The method of claim 14, further comprising:

displaying the image using one of a plurality of high level voltages according to the luminance band;

supplying one of a plurality of parking voltages corresponding to said one high level voltage during the stress period; and

determining the width of the stress period according to the supplied parking voltage.

16. The method of claim 14, wherein the lookup table stores a correspondence relation of the luminance band and a plurality of parking voltages of the stress signal and a correspondence relation of the plurality of parking voltages and the width of the stress period.

17. The display device of claim 1, wherein the display panel displays the image using one of a plurality of high level voltages as the high level signal according to the luminance band,

wherein the timing controlling circuit is configured to determine the width of the stress period according to the one of the plurality of high level voltages, and wherein the width of the stress period is reduced as a voltage value of the one of the plurality of high level voltages is reduced.
